Joseph Burns INVENTOR

BY Victor J. Evans

ATTORNEY

WITNESS:

UNITED STATES PATENT OFFICE.

JOSEPH BURNS, OF OKMULGEE, OKLAHOMA.

TEMPER SCREW.

Application filed March 4, 1924. Serial No. 696,893.

To all whom it may concern:

Be it known that I, JOSEPH BURNS, a citizen of the United States, residing at Okmulgee, in the county of Okmulgee and State of Oklahoma, have invented new and useful Improvements in Temper Screws, of which the following is a specification.

This invention relates to improvements in temper screws employed in connection with drilling apparatus for oil wells, and serving to lengthen the stroke of the drill as the work proceeds, in order that the bit may strike the lower end of the bore on each working stroke.

Further objects include the provision of wear adjusting means at the point where the member termed an elevator is connected with the jockey stick; the provision of a particular type of yoke for the split nut, or box, with which the screw cooperates, and the provision of an anti-friction bearing between the swivel block and the transverse handle bar carried by the screw just above the swivel block.

With the foregoing and other objects in view, the invention consists in the novel construction and arrangement of elements described illustrated and claimed, it being understood that modifications may be made within the scope of the claims without departing from the spirit of the invention.

In the drawings, Figure 1 shows the device in side elevation; Figure 2 is a vertical section, showing the principal operative elements; Figure 3 is a section on line 3—3 of Figure 1; Figure 4 is a fragmentary side elevation showing clamping means for the threaded box members with reference to which the screw is to be adjusted vertically; Figure 5 is a top plan view of an upper transverse bar having an angular or hexagonal socket the size of which may be varied to fit the end of a jockey stick and compensate for the wear at that point; Figure 6 is a section through the threaded box elements adapted to be clamped to the screw; Figure 7 is a yoke member adapted to surround the elements of Figure 6.

The reins 10 include parallel bars such as 11 connected at the upper ends with a shank 12 carrying a cross bar 13 forming a T element to be supported from a walking beam, not shown.

The boxes 14, 14' are formed respectively on the lower ends of bars 11, are threaded

internally at 15, and constitute a split nut cooperating with the main screw 16.

The upper end of screw 16 enters a socket 17 in transverse bar 18 constituting an elevator, and the ropes or cables 19 at the ends of the elevator pass over pulleys 21 supported from hooks 22 and the T member 13. Cables 19 are connected with weight box 23, serving the usual purpose.

An important feature of the construction of the elevator is the adjustment provided in connection with the mounting of the jockey stick 25. This stick passes through longitudinal bore 26 in the main screw 16, and has hexagonal or other angular end portion 27 received by the angular socket 28 at the central portion of the elevator. (A cross section of the jockey stick near the end corresponds with the form of the extreme end.) An enlargement 29 provides a bore 30 for bolt 31 which extends at an angle with a slot 32, formed in the enlarged portion, and extending between the outer edge thereof and the socket 28. The adjustment of nut 33 on this bolt serves to take up wear between the end of the jockey stick and the socket 28. Guides 34 in elevator 18 cooperate with the parallel members of the reins 10.

A yoke is employed for mounting a screw for clamping the elements of the split nut, otherwise termed box members 14, 14'. The yoke is designated 35, and includes an elliptical frame having a threaded socket 36 formed thereon for threaded shank 37 of handle 38. The shank 37 passes into the yoke and engages box 14, for tightening the latter on the screw.

Box 14' is curved to conform to the curvature of the yoke, and an outer segmental 95 groove or channel 39 cooperates with the edge of the yoke and overlaps the latter. Element 14' is retained by set screw 40 passing through elements 35 and 14'. In order to prevent displacement when the screw becomes loose, the yoke is provided with lugs or stops 41 which are engaged by the flattened portions 42 on member 14', the flanges of the channel being cut away at this point for the purpose indicated. If the lugs 41 wear down sufficiently to permit turning movement of element 14', the ends of element 14 will prevent undue rotation.

The lower end of the screw has a head 45 formed thereon, this head being positioned

within socket 46 of swivel block 47, rotatable on the screw and separated from the head by ball bearing 48. Jockey stick 25 has a T end portion 49 bolted to the swivel block, 5 and the stick passes loosely through the bore of the main screw.

When there is no weight on the swivel block 47, the weight box 23 will exert a pull 10 on elevator 18, jockey stick 25, and on T member 49, tending to lift the swivel block and bring it into engagement with the central portion of transverse handle bar 50, by which the screw is taken up and by which the screw is rotated with reference to the swivel 15 block and reins.

The engagement specified makes it difficult to turn handle bar 50, and in order to overcome the difficulty mentioned, I provide a ball bearing 51 between the hub or boss 20 50' of the handle bar, and the swivel block, thereby eliminating friction, and facilitating to a marked degree the operation of the device.

The apparatus is to be carried by a walking beam, in the usual manner. A cable for supporting the drill is suspended from the swivel block 47, and as the drilling proceeds, bar 50 is operated for the purpose of increasing the effective length of screw 16 by rotating it with reference to the box comprising elements 14, 14'. Thus the drill may be caused to advance at the proper rate and strike the bottom of the bore at each stroke.

What I claim is:

35 1. In a device of the class described, a

screw having a longitudinal bore, a jockey stick extending through the bore, a transverse lifting bar having an angular split socket, the end of the stick having flat sides for engaging the socket, and a device passing 40 through the bar beyond the socket, at the split portion, a transverse element on the lower end of the stick, stationary threaded means with reference to which the screw is rotatable, a swivel block supported by the 45 transverse element on the stick, a transverse element for rotating the screw and mounted above the block, and antifriction means preventing the swivel block from engaging the transverse element by which 50 the screw is rotated.

2. In a device of the class described, a screw having a longitudinal bore, a jockey stick extending through the bore, a transverse element on the lower end of the stick, stationary threaded means with reference to which the screw is rotatable, a transverse lifting bar connected with the stick and having a split socket formed therein, means 55 for varying the effective size of the socket to compensate for wear between the end of the stick and the socket receiving it, a swivel block loosely mounted with reference to the lower end of the screw, and means for turning the screw with reference to the stationary threaded means, said swivel block being connected with the transverse element on the lower end of the stick.

In testimony whereof I affix my signature.

JOSEPH BURNS.
